UNITED STATES PATENT OFFICE.

WASHINGTON B. VANDERLIP, OF NEW YORK, N. Y.

COLLISION AND TORPEDO MAT AND APPARATUS FOR MANIPULATING SAME.

1,265,555.

Specification of Letters Patent. Patented May 7, 1918.

Application filed July 11, 1917. Serial No. 179,827.

To all whom it may concern:

Be it known that I, WASHINGTON B. VANDERLIP, a citizen of the United States, and resident of New York, in the county of New York and State of New York, have invented certain new and useful Improvements in Collision and Torpedo Mats and Apparatus for Manipulating Same, of which the following is a specification.

The present invention relates to improvements in collision and torpedo mats and apparatus for manipulating the same.

Many steamships or other sailing vessels, now lost as the result of collision, torpedoing, etc., could be saved or kept from sinking quickly if the amount of water entering be limited. In many cases, this limitation has been provided by the application of a collision mat over the opening made, but such instances are few and are generally possible only where the hole made does not extend materially below the water line, so that the accumulation of water will not be sufficient to sink the vessel before a makeshift mat can be rigged up and placed in position. Since the formation and rigging of a collision mat, under present conditions, requires a considerable length of time, the percentage of vessels saved by this method is small; the vessel sinking before a mat can be produced and placed in position.

The present invention is designed to overcome these conditions to a considerable extent by making it possible to place a mat in position over the opening in a short space of time. For instance, under the operations of the present invention, it is possible to position an efficient mat over an opening amidship within a period of, approximately, three minutes from the time of explosion, even where the mat has a size of forty feet in length by eighteen feet in width, an area sufficient to provide a proper covering for the largest sized openings generally produced by torpedoes. As vessels generally do not sink in such a short period of time, it is possible not only to increase the length of time required for the vessel to sink, where the injury is too bad to permit saving of the vessel, but, in most cases, to permit the vessel to be saved.

The successful operation of apparatus for this purpose is more or less dependent on a number of factors. For example, its simplicity of operation and its effectiveness when applied. The cost of installation may

be another factor. In addition, the apparatus should not interfere with the movements of the vessel, and it should not become deteriorated by having essential elements normally located in the water where chemical action may affect the integrity of the elements.

The present invention is designed to meet these conditions, and consists in the improved construction and combination of parts hereinafter fully described, illustrated in the accompanying drawings, and more particularly pointed out in the appended claims.

In the drawings, in which similar reference characters indicate similar parts in each of the views—

Figure 1 is a diagrammatic view in elevation—parts being broken away—of the bow of a vessel equipped with apparatus according to the present invention.

Fig. 2 is a fragmentary view in side elevation showing a mat in position over an opening in the hull of the vessel.

Fig. 3 is a detail sectional view showing one form of trolley support.

Fig. 4 is a detail sectional view of a preferred mat structure.

Fig. 5 is a diagrammatic view of a vessel with the mat in position.

Fig. 6 is a detail elevation showing the manner in which the mat is normally supported.

Figs. 7 to 10, inclusive, are diagrammatic views indicating successive stages in the manipulation of the apparatus.

The mat structure may be of any suitable type, that preferred being formed of canvas plies or layers 20 of the desired length and width, these layers being connected together in suitable manner and having steel or other metal rods or pipes 21 extending therebetween, as, for instance, shown in Fig. 4. The rods 21 extend lengthwise of the mat, preferably in parallel relation, being spaced apart suitable distances. The upper end of the mat is preferably secured to a steel angle bar 22 by suitable means, as by lashings. If desired, the lower end 105 may be similarly formed. This general arrangement will not only permit of ready collapsing, as by folding or rolling, but, with the use of rods of one-half to three-fourths of an inch in diameter, and spaced apart a distance of approximately five inches, the mat practically becomes a flexi-

ble steel mat which may have a length of forty feet and over, and a width of eighteen feet or more, a mat capable of completely covering the hole made by a torpedo, and 5 having a strength sufficient to withstand such water pressures as the mat is required to resist.

The mat, when positioned for emergencies, is collapsed and secured in such condition 10 by suitable lashings 30. The folded mat is supported outboard by a suitable trolley structure, this structure being shown as a plurality of trolley units 23, each unit having a pair of wheels 24 adapted to travel on 15 a track 25, and a guiding member 26 overhanging a track 27 extending parallel to and above track 25. Tracks 25 and 27 preferably extend from bow to stern outside of the vessel adjacent the rail. Units 23 may 20 be independent of each other, but I prefer to connect them together by a suitable line 28. The several units are connected to bar 22 by lashings 29. Obviously, any desired number of units may be employed.

25 I prefer to employ at least two mat structures, one to starboard and the other to port, these being normally positioned at the bow of the vessel. As shown in Fig. 1, the general arrangement brings the triced collapsed 30 mat close to the rail of the vessel above the water line and at a point close to the bow. As will be understood, the general trolley structure is such that the mat can be stored away and quickly placed in position when 35 approaching a point of possible danger.

By means of the trolley arrangement, the mat can be quickly shifted to any point along tracks 25 and 27, a hauling line 31 being connected to the first unit and carried 40 outboard, this line permitting the mat to be drawn to the point of use.

The manipulation of the mat in placing it in operative position will be more particularly understood from Figs. 7 to 10, inclusive, which disclose the various lines, etc., and the manner of their manipulation in the positioning operation.

Fig. 7 indicates diagrammatically the normal arrangement of parts, mat *a* being positioned on the starboard side and mat *b* on 50 the port side. 32 indicates the keel line for mat *a*, this line having one end secured centrally of the bottom of the mat (Fig. 2), from which point it leads successively to a 55 coil 32^a, a sand bag 32^b, a coil 32^c and a trolley hanger 32^d, these parts being arranged on deck, preferably about as shown in Fig. 7. Coils 32^a and 32^c are of the usual line coil type which permits of unwinding 60 in both directions without fouling. Bag 32^b is of a size to carry a suitable quantity of gravel or sand—for instance, 300 pounds—and is preferably formed with an opening of suitable size at its bottom, this opening being 65 normally closed by a string or lash

readily released. The keel line 33 for mat *b* is of similar arrangement.

Assuming the mat crew to be at their stations on the deck and a torpedo explosion as taking place on the starboard side, keel 70 line 32 is thrown over the bow of the vessel as indicated in Fig. 8, coil 32^a being thrown to starboard, coil 32^c to port, trolley hanger 32^d placed in position on the port tracks 25 and 27, aft of mat *b*, and the sand bag 75 32^b, after destroying the lashing of the bag opening, tossed over the bow. This action causes the sand bag to carry the keel line beneath the keel, the two ends of the line being connected to the bottom of the mat *a* 80 on one side of the vessel, both ends being easily carried aft by reason of the trolley arrangement.

The lashings which normally position the mat and trolley structure at the bow are 85 now cut, and the mat drawn aft by hauling line or lines 31 until the mat (still collapsed) reaches a position above the hole. The lashings of lines 34 (which lead from bar 22 over the rail) are cut, and the inner ends 90 of such lines hitched to any convenient part of the vessel deck. For instance, in Fig. 9, one line is shown as hitched to a stairway, another to stanchions, and others to I-bolts.

Lashings 30 are now cut, permitting the 95 mat to open out, and the opposite end of the keel line removed from hanger 32^d and brought inboard. Lashings 29 are then cut and the mat permitted to move downward by paying out lines 34, until it is properly 100 located over the hole (Fig. 2), the keel line being drawn in over the port rail to aid in this operation, the free end of this line being secured in position by suitable means, as, for instance, a block and tackle 35, which 105 may be secured at one end to the starboard rail.

As will be understood, the opening in bag 32^b has permitted the contents to be discharged, so that by the time the final securing is had—a period of less than four minutes with a trained crew—the bag will be 110 empty and offer no material weight to be taken care of, nor obstacles to outer lash lines.

The positioning of the mat plugs the hole and prevents material ingress of water, the mat structure being of a type which will withstand the water pressures which may be encountered. If desired, additional lines 115 120 may then be placed in position over the mat by applying a sand bag to the line and casting it over the bow of the vessel, the ends of the lines then being brought inboard and secured in position.

125 As will be understood, the all-important factors are met by this arrangement.

The question of weight of mat is practically eliminated by the fact that the mat is moved on a predetermined trackway while 130

the mat is collapsed and hence not impeded by the water. The mat may therefore be of any desired size and of substantial material, insuring that the hole will be efficiently plugged and closed, ample portions of the mat extending over the adjacent parts of the hull to aid in maintaining the integrity of the mat.

The time required to position the mat is reduced to a minimum. With the crew at their stations, when entering the danger zones, the manipulations can be started the instant the explosion takes place and it becomes known whether the explosion is on the starboard or port side. The keel line is thrown overboard while the exact point of explosion is being ascertained and the mat and free end of the keel line started aft without delay, by drawing on lines 20 31, which may normally extend along the rail in position to be grasped by assistants to bring the mat quickly to position. The downward movement of the mat may be had with rapidity, closing the opening 25 by the pressure of the water, the largely increased size of the mat preventing it from being forced through the opening, so that closing may be had prior to the securing of the lines in position.

30 The mat in secured position provides an efficient closure, it being understood that torpedo explosions are generally inward, so that no material rough edges are presented externally. The manner in which the lines 35 are secured to the vessel insures the mat remaining in position. Rapid closing of the opening will oftentimes prevent the entrance of sufficient water to endanger the vessel through internal explosions.

40 The cost of installation is relatively small, the portability of the mat enabling the vessel to be protected by the use of but two mats, this portability increasing the rapidity of operation by reason of the fact 45 that the proper keel line may be made ready in advance of determining the exact location of the opening.

All of the elements are normally above the water line and therefore offer no resistance 50 to the normal movement of the vessel and at the same time any deteriorating effect of the water is prevented.

While I have herein shown and described a preferred arrangement of parts and of 55 manipulating them, it is obvious that variations and modifications therein may be found necessary or desirable to meet the exigencies of service conditions, and I therefore desire to be understood as reserving 60 the right to make any and all such changes or modifications therein as may be found essential or desirable in so far as the same are permitted by the spirit and scope of the invention as expressed in the accompanying 65 claims when broadly construed.

Having thus described my invention, what I claim as new is:

1. The combination with a vessel of an outboard support extending in the direction of the length of the vessel and a mat 70 structure normally carried by and shiftable lengthwise on said support, said structure having means connected with the support to permit positioning of the mat over an opening in the hull, said means including a 75 keel line connected to the mat structure and carrying a weight operative to sink the line when cast overboard and gradually decrease the weight factor during travel of the line to position.

2. The combination with a vessel of an outboard trolley support, extending in the direction of length of the vessel above the water line, a mat structure having a trolley unit mounted and rapidly shiftable on the 85 support, detachable means between the trolley unit and mat to permit the latter to be positioned over an opening in the hull, said mat structure including positioning lines normally carried thereby and adapted to be 90 rapidly secured inboard at the point of structure application and in advance of release of the detachable connections, and a keel line connected to the mat structure and carrying a weight operative to sink the line 95 when cast overboard and gradually decrease the weight factor during travel of the line to position.

3. As a means for rapidly positioning a mat over an opening in the hull of a vessel, 100 an outboard support extending in the direction of length of the vessel, a mat structure normally carried by and shiftable lengthwise on said support, a keel line connected to the mat and having means normally located inboard to permit its rapid positioning beneath the keel of the vessel, said keel line carrying a weight structure operative to sink the line when cast overboard and gradually decrease the weight factor during 105 travel of the line to position, detachable connections between the mat and its support, and lines for supporting the mat when detached from the support.

4. The combination with a vessel, of outboard supports extending in the direction of length of the opposite sides of the vessel above the water line, a mat structure carried by and shiftable lengthwise on one of said supports, said structure being normally 120 positioned at the bow of the vessel, a keel line connected to the mat structure and having a hanger at its free end normally located inboard and adapted to be mounted on the support at the opposite side of the vessel, said line having means whereby it may be cast over the bow of the vessel and positioned beneath the vessel keel, detachable connections between the mat and its support whereby the mat may be located 125 130

above a hull opening to be closed, detaching of the mat from its support, permitting the mat to be lowered over the opening, and means for supporting the mat in its lowered position.

5. The combination with a vessel, of out-board supports extending in the direction of length of the opposite sides of the vessel above the water line, a mat structure carried
10 by and shiftable lengthwise on one of said supports, said structure being normally positioned at the bow of the vessel, a keel line connected to the mat structure and having a hanger at its free end adapted to be
15 mounted on the support at the opposite side of the vessel, said line having means whereby it may be cast over the bow of the vessel and positioned beneath the vessel keel, detachable connections between the mat and its
20 support, whereby the mat may be located above a hull opening to be closed, detaching of the mat from its support permitting the mat to be lowered over the opening and means including the keel line for maintaining the mat in its lowered position.

6. The combination with a vessel, of out-board supports extending in the direction of length of the opposite sides of the vessel above the water line, independent mat structures for and shiftable lengthwise of the supports, said structures being normally positioned at the bow of the vessel, and means individual to each structure for rapidly positioning it at its point of applica-
30

tion relative to the hull of the vessel, said means including a securing line normally located inboard, said line having one end secured to the mat structure and having its other end carrying a member adapted to be positioned on the opposite support. 35

7. The combination with a vessel, of out-board supports extending in the direction of length of the opposite sides of the vessel above the water line, independent mat structures for and shiftable lengthwise of the supports, said structures being normally positioned at the bow of the vessel, and means individual to each structure for rapidly positioning it at its point of application relative to the hull of the vessel, said 40 means including a securing line normally located inboard, said line having one end secured to the mat structure and having its other end carrying a member adapted to be positioned on the opposite support, the intermediate portion of the line carrying a 45 weight structure operative to sink the line when cast overboard and gradually decrease the weight factor during travel of the line to position. 50

Signed at New York in the county of New York and State of New York, this 10th day of July, A. D. 1917.
